LAMP REGULATING SYSTEM

Willem F. Westendorp, Schenectady, N. Y., assignor to General Electric Company, a corporation of New York

Application July 13, 1939, Serial No. 284,271

2 Claims. (Cl. 176—124)

The present invention relates to improved means for operating positive column lamps.

Because of their possession of a negative volt-ampere characteristic, lamps of the nature specified are not inherently current limiting. For this reason it is common practice to provide ballasting means, such as a series resistor or reactor, in the lamp circuit. This expedient prevents runaway operation, but has an adverse effect on either the efficiency or the power factor of the system as a whole. It is an object of my present invention to provide a novel lamp-regulating means by which both these effects are minimized.

In the attainment of the foregoing object, an important aspect of the invention consists in the provision in the lamp itself of discharge-controlling means which so regulate the discharge cycle as to produce substantially constant current operation. More specifically, the invention employs, in a preferred embodiment thereof, a lamp having a single cathode and a plurality of anodes, each anode being associated with a control electrode or grid. By applying to the various grids alternating control potentials which are variable in accordance with the discharge current, the transfer of such current from one anode to another is regulated in a desired fashion, and the average current flow is thereby kept within proper limits.

The features of the invention which I desire to protect herein are pointed out with particularity in the appended claims. The invention itself, together with further objects, and advantages thereof, may best be understood by reference to the following description taken in connection with the drawing; in which Fig. 1 illustrates diagrammatically the combination of a positive column lamp and a circuit for operating the same in accordance with the principles of my invention; Fig. 2 comprises a series of graphical representations useful in explaining the invention; and Fig. 3 illustrates the operating characteristics obtainable by the use of the invention.

Referring particularly to Fig. 1 there is shown a discharge lamp comprising a tubular envelope 10 which is constituted of a light-transmitting material such as glass. The envelope terminates at one end in a bulbous portion, designated by the numeral 11, and at the other end in a pair of oppositely directed arms, numbered 13 and 14 respectively. The lamp is of sufficient length so that the tubular portion 10 provides an elongated positive column space.

Within the bulbous portion 11 of the envelope, there is provided a quantity of vaporizable, ioniz-

able material, for example, mercury, this being shown at 15. This material is adapted to serve as a cathode for a discharge passing through the lamp, and further provides a source of excitable ions which, during the use of the lamp, cause light emission to occur. If desired, the mercury cathode 15 may be replaced by a solid separately heated cathode, in which case a separate ionizable material, for example, neon gas or a mixture of gases, should be provided as a filling for the envelope. A fixed gas may also be used advantageously even where a vaporizable cathode is employed.

Above the cathode and preferably outside the envelope there is provided a capacity starting band 18 of conductive material which serves to facilitate the initiation of a discharge from the cathode. At the other end of the lamp, within the side arms 13 and 14 there are mounted a pair of anodes 20 and 21 which provide alternately functioning terminals for a discharge proceeding from the cathode 15. For the purposes of the present invention, these anodes are respectively enclosed within perforated grid members designated by the numerals 23 and 24. The utility of the grids 23 and 24 will be described hereinafter.

In the arrangement shown in Fig. 1, the lamp is energized from an alternating current source, indicated at 25. The energizing circuit includes a pair of similar branches 26, 27 which are respectively connected to the terminals of an auto-transformer 28. These circuit branches are connected at their terminals to the anodes 20 and 21 and have a common junction point 29 (a midpoint tap of the transformer 28) which is connected through a conductor 31 to the cathode 15. When the system is energized by closure of line switch 32, the lamp operates as a full wave rectifier, producing a continuous discharge which passes alternately to the anodes 20 and 21. The discharge current is caused to pass through a reactor 34 whose function will be described more fully hereinafter.

In order to render the lamp initially operative a special starting circuit is provided in connection with the starting band 18. This circuit connects the band 18 with one terminal of the auto-transformer 28 through a conductor 35, a current-limiting resistor 36 and conductors 37 and 21. During inoperative periods of the lamp, the starting band 18 is shorted to the cathode 15 through a mercury switch 38 which is movable under the influence of an armature 40 associated with the reactor 34. As soon as the switch 32 is

closed, a transient surge is produced in the reactor 34 through a circuit which includes conductor 31, the reactor, switch 38, resistor 36, and conductors 37 and 21. This surge causes motion of the armature 40 and a consequent tilting of the mercury switch 38 to open its circuit (the switch being thereafter maintained open). At the instant of opening, the relatively high transient voltage existing across the reactor 34 is impressed between the starting band 18 and the cathode 15 and acts to cause a discharge to be initiated. This discharge is immediately transferred to the anodes 20 and 21 and is subsequently maintained by these anodes.

In order to limit current flow through the lamp 10 and at the same time to assure high efficiency and good regulation of the system as a whole, a special regulating circuit is provided in connection with the grids 23 and 24. For reasons which will be brought out in the following, it is desirable that the energization of these grids be made to depend upon the current flow in the discharge circuit. To this end, intermediate terminals 41 and 42 of the auto-transformer 28 are brought out and connected to the primary winding 44 of a regulating transformer 45. The winding 44 is connected at its midpoint to the cathode supply conductor 31, so that half of the winding is in series with the circuit branch which supplies the anode 20, while the other half is in series with the circuit branch which supplies the anode 21. The transformer 45 is provided with a secondary winding 46 having a greater number of turns than the primary winding 44 so that voltage step-up is accomplished. This secondary winding is connected at its respective terminals to the grids 23 and 24 and thus serves to control their potential. A shunting arrangement comprising a condenser 48 and a resistor 49 is provided across the secondary winding 46 and serves to fix the phase relationship between the voltage applied to the grids and the current flow in the primary circuit, these quantities being obviously proportional in magnitude.

The operation of the system above described is as follows: After the tube has been started and the current has reached the value set by the grid control, the discharge current flowing through the primary of the transformer 45 develops a voltage across the condenser 48 which lags with respect to the current. With the connections shown, the grid associated with any given anode becomes negative during the period when the other anode is carrying current. Furthermore, the negative polarity of such grid is maintained through the point at which commutation of the discharge to its associated anode tends to occur. The transfer of the current from one anode to the other is, therefore, regulated by the grid voltage and, more fundamentally, in accordance with the variations of the discharge current itself.

The fact that the grid circuit is "floating" (i. e. not connected to any of the other electrodes) simplifies the circuit and improves its operation. The grid around the running anode can never be more positive than that anode. Consequently, if the transformer 45 is connected in the proper way, the grid associated with the inactive anode will be negative when the arc current first tends to shift to that anode and will thus delay the instant of shifting.

It is the function of the reactor 34 to exert a smoothing effect on the discharge current and thereby to reduce flickering of the lamp. Fur-

thermore, the current-sustaining effect of the reactor avoids the possibility of extinguishment of the discharge at the end of any given voltage cycle. That is to say, the presence of inductance in the system causes current flow to continue even though the voltage supplied by the auto-transformer 28 may be instantaneously reduced to zero.

The mode of operation described in the foregoing and the results which it accomplishes may be better understood by referring to the graphical representation of Fig. 2. In this figure the voltage curves V_1 and V_2 respectively represent the voltage applied between the point 29 and the anode 20 and that applied between the point 29 and the anode 21. The curves I_1 and I_2 , on the other hand, represent the resulting pulses of unidirectional current flow to the two anodes. The control voltages applied to the grids 24 and 23 are indicated by the curves e_2 and e_1 respectively. It will be understood that the magnitude of the control voltage curves is proportional to that of the current curves and that these curves are displaced in phase due to the action of the condenser 48.

It is assumed that the lamp initially becomes conductive at the instant t_0 when the voltage V_1 has reached a predetermined positive value. As the current I_1 tends to increase, the potential applied to the grid 24 increases in a negative sense as indicated by the curve e_2 . At a later time, as the current I_1 begins to diminish in accordance with the previous decrease of the voltage V_1 , the voltage e_2 also decreases in negative magnitude. As the latter quantity reaches a critical releasing value e_0 (at time t_1), the anode 21 is "triggered" and the discharge transfers to that anode. The current through the lamp again increases in accordance with the curve I_2 , and the cycle is repeated. Each grid assumes space potential as soon as it becomes positive with respect to the other grid.

In the event that the average value of current through the lamp tends to increase, as indicated, for example by the curve I_1' , the negative grid voltage similarly increases to a value e_2' , and commutation of the discharge is delayed to a time t_2 . As a result, the average potential supplied by the auto-transformer during the next succeeding conducting interval (being made up of a shortened positive component and a lengthened negative component) is reduced and the average current flow is diminished accordingly. Since this regulatory effect occurs for each current cycle, it will be understood that stability of the system as a whole is assured.

The type of regulation obtained with a circuit such as that described above is illustrated in Fig. 3 wherein the curves A and B respectively represent characteristics obtained by varying the line voltage with two different adjustments of the elements 48 and 49. In these curves, the decrease in current noted as one approaches higher values of operating line voltage is primarily a result of increased magnetizing current flowing through the auto-transformer 28, such magnetizing current producing a change both in the magnitude and phase of the control voltage applied to the grids 23 and 24. Obviously a less drooping characteristic could be obtained by use of a transformer of greater capacity.

The point x is assumed to be taken at the approximate center of the desired operating range of the lamp. Under these conditions and especially for the curve A, it will be seen that sub-

stantially flat regulation of the system may be obtained for an appreciable range of voltage variation. This is a result which is quite unobtainable when regulation is sought simply by the use of series ballasting means. In the latter case, the lamp current tends to increase linearly with the line voltage, as indicated, for example, by the dotted line C of Fig. 3.

The system described represents a marked improvement in efficiency over systems employing resistor control in that the regulation obtained involves no dissipation of power. Furthermore, although some effect on power factor is to be noted as a result of the phase shift of current and line voltage due to the grid control, this effect is materially less than that occurring in cases where a series reactor is used in the alternating current supply line as a ballasting means or where a high reactance power transformer is employed.

What I claim as new and desire to secure by Letters Patent of the United States is:

1. In combination, a positive column lamp having a cathode and a pair of anodes, a current supply circuit for said lamp including a pair of similar circuit branches having a common junction point, the said branches being connected at their respective terminals to the said anodes and being connected at their said junction point to the cathode through a series reactor, a source of alternating potential connected in said current supply circuit so as to produce through the lamp a discharge which tends to transfer cyclically from one anode to the other, a pair of grids respectively associated with the said anodes and effective to control the initiation of a discharge

thereto, and a transformer including a primary winding having similar parts thereof respectively connected in series with both of the said circuit branches and a secondary winding terminally connected to the said grids, whereby regulation of the lamp is accomplished by controlling the transfer of the discharge from one anode to the other in automatic response to variations in magnitude of the discharge current.

2. In combination, a positive column lamp having a cathode and a pair of anodes, a current supply circuit for said lamp including a pair of similar circuit branches having a common junction point, the said branches being connected at their respective terminals to the said anodes and being connected at their said junction point to the cathode, means including a source of alternating potential connected in said current supply circuit to produce through the lamp a discharge which tends to transfer cyclically from one anode to the other, a pair of grids respectively associated with the said anodes, each such grid being effective to control the initiation of a discharge to its associated anode in accordance with the variations of a voltage applied to the grid, and means for applying an alternating voltage to the said grids for regulating the transfer of the discharge from one anode to the other, the said voltage applying means being excited responsive to current flow in the said current supply circuit, whereby the regulating action of such means varies in direct response to variations in the magnitude of the discharge current and in a manner tending to maintain the discharge current relatively constant.

WILLEM F. WESTENDORP.
